UNITED STATES PATENT OFFICE

1,933,983

BUST BODICE OR BRASSIÈRE

Rosamond Lilian Kennedy, Hyde Park,
London, EnglandApplication July 29, 1930, Serial No. 471,479, and
in Great Britain October 12, 1929

7 Claims. (Cl. 2—30)

This invention relates to bust bodices or brassières for women's wear of the kind having breast supports of substantially triangular form overlapping or intersecting in front and wherein a tension is produced along the inner edge of each support by the combined action of shoulder straps and lateral straps or bands passing from the outer corner of each support round the wearer's body to the inner corner of the same support, or an equivalent point on the base of the other support.

A bust bodice of this kind is described in my United States patent specification No. 1,681,119 dated 14th August 1928.

15 An object of the present invention is to adapt a bust bodice of the type described for wear more especially with women's evening gowns or other garments cut low in the back so that the crossing straps or bands shall not be visible.

20 According to the present invention the straps or bands which cross the back of the wearer are drawn down and connected to some other garment such for example as a belt or corset at a point or points lower than that at which the straps or bands would normally pass, connections from said point or points to the fronts of the actual supports being made either by continuing the same straps or bands, or providing separate ones, or by means of the upper edge of 25 the garment, such as the belt or corset, to which the bands are attached, the said garment in such case having means for attachment to the lower edges of the breast supports at or near their inner corners.

30 35 The belt, corset or other like garment may be made higher in front than behind in which case the lower edges of the breast supports may be directly attached thereto either detachably as by buttons or the like fastening or with a permanent attachment as by sewing in which case the bust bodice may be sewn or otherwise permanently attached to or made integral with the corset, belt or other garment along the lower edge of the overlapping portions of the supports.

40 45 If the upper edge of the belt or corset is substantially at the same height both in front and behind there will be a gap all the way round between belt or corset and bust bodice and the attachment between the two garments in front may conveniently be by short straps substantially prolonging the lines of the inner edges of 50 the overlapping breast supports.

45 55 The straps crossing the back of the wearer from the outer corners of the breast supports may conveniently be continuous from the outer

corner of one support to the outer corner of the other support, connection with the upper edge of the belt or corset being effected by passing the single connecting strap thus formed through a loop or loops attached to said upper edge near the midpoint of the back.

In order that the nature of and manner of carrying out the present invention may be more fully understood one form of construction is described with reference to the accompanying drawing of which:

Figs. 1 and 2 are front and back views of one form of construction.

Fig. 3 is another front view showing an alternative front attachment.

Referring to the drawing:

A, A¹ are substantially triangular breast supports overlapping in front and having a common base line D, D¹.

A shoulder strap E or E¹ is attached at the apex of each of the supports and passes over the adjacent shoulder of the wearer to the outer extremity F or F¹ of the breast support, (see Fig. 2).

Connecting the points F, F¹ is a strap E² which may be continuous with the shoulder straps E, E¹ and which is passed through a loop G attached in the middle of the back of the wearer to the upper edge H^x of a corset or belt H.

The inner extremities D, D¹ of each support, A, A¹ are attached to the upper edge H^x of the belt or corset H, either directly, as in Fig. 1 by means, for instance, of a tab having a buttonhole, or, as in Fig. 3 by means of short extensions or straps, K, K¹ substantially prolonging the line of the inner edges of the breast supports A, A¹, buttons being conveniently provided on the upper edge H^x of the belt or corset H, as at D, D¹ in Fig. 1 or as at L in Fig. 3, the corresponding attachment on the left side of the wearer being (in Fig. 3) hidden by the curve of the wearer's body.

Thus the pull of the shoulder strap E is taken along the inner edge of the support A to the inner extremity D and thence either directly (Fig. 1) or by means of an extension K (Fig. 3) to the upper edge H^x of the belt or corset H and along such upper edge H^x round the wearer's back to the loop G and thence by means of the strap E² to the outer extremity F of the support A, and so to the other end of the shoulder strap E.

Similarly for the other support A¹ the pull of the shoulder strap E¹ is taken through the point D¹, the upper edge H^x of the belt H and the strap E² to the point F¹ at the outer extremity of the support A¹.

What I claim is:

1. In a combined foundation garment for women's wear, adapted to be worn beneath a gown having a low décolletage at the back and consisting of a lower part fitting closely to the wearer's 5 hips and having in wear its upper edge at the back located approximately on the natural waistline and a brassière comprising a pair of breast supports constituted by two substantially triangular pieces of material intersecting in front so as to 10 have a common base line for part of their length together with a pair of shoulder straps, a loop attached to said upper edge at the middle of the back and a strap interconnecting the outer extremities of said breast supports said strap being 15 passed through said loop.

2. In a combined foundation garment for women's wear, adapted to be worn beneath a gown having a low décolletage at the back and consisting of a lower part fitting closely to the wearer's 20 hips and having in wear its upper edge at the back located approximately on the natural waistline and a brassière comprising a pair of breast supports constituted by two substantially triangular pieces of material intersecting in front so as to 25 have a common base line for part of their length together with a pair of shoulder straps, a loop attached to said upper edge at the middle of the back, a strap inter-connecting the outer extremities of said breast supports, said strap being passed 30 through said loop and a connection between the inner extremity of said breast support and said upper edge of the lower part of the garment.

3. In a combined foundation garment for women's wear, adapted to be worn beneath a gown 35 having a low décolletage at the back and consisting of a lower part fitting closely to the wearer's hips and having in wear its upper edge at the back located approximately on the natural waistline and a brassière comprising a pair of breast supports constituted by two substantially triangular pieces of material intersecting in front so as to 40 have a common base line for part of their length together with a pair of shoulder straps, a loop attached to said upper edge at the middle of the back, a strap interconnecting the outer extremities of said breast supports said strap being passed 45 through said loop and a connection between the inner extremity of said breast support and said upper edge of the lower part of the garment, said 50 connection including a short strap.

4. In a combined foundation garment for women's wear adapted to be worn beneath a gown having a low décolletage at the back and consisting of a brassière comprising a pair of breast 55 supports constituted by two substantially triangular pieces of material overlapping and secured together in front so as to have a common base line for part of their length together with a pair of shoulder straps and a lower part fitting 60 closely to the wearer's hips and having in wear its upper edge at the back located approximately on the natural waistline, connecting means for securing said brassiere to the upper edge of said lower part of the garment at both the front and 65 the back, the back connecting means comprising straps attached to the outer extremities of the said breast supports and arranged substantially in a wide angled V for attachment to the upper edge of said garment lower part near the middle 70 of the back thereof and the front connecting means disposed between the outer ends of said common base line of the breast supports and the upper edge of said lower part of the garment, the lower edge portions of said breast supports outwardly of said common base line being free; the 75

free portions of the upper edge of said lower part of the garment laterally of the said front connecting means being shaped and positioned substantially in continuation of the inner upper crossed edges of the breast supports to serve in conjunction with said front and back connecting means for producing tensions along said inner upper edges of the breast supports.

5. In a combined foundation garment for women's wear adapted to be worn beneath a gown having a low décolletage at the back and consisting of a brassière comprising a pair of breast supports constituted by two substantially triangular pieces of material overlapping and secured together in front so as to have a common base line for part of their length together with a pair of shoulder straps and a lower part fitting closely to the wearer's hips and having in wear its upper edge at the back located approximately on the natural waistline, back connecting means attached to the outer extremities of the said breast supports and extending downwardly therefrom in a wide angled V for attachment to the upper edge of said lower part of the garment near the middle of the back, front connecting means disposed between the outer ends at least of said common base line of the breast supports and the upper edge of said lower part of the garment leaving the portions of the lower edges of said breast supports located outwardly of said common base line free; the free portions of the upper edge of said lower part of the garment laterally of the said front connecting means being shaped and positioned substantially in continuation of the inner upper edges of the breast supports to serve in conjunction with said front and back connecting means for producing tensions along said inner upper edges of the breast supports.

6. In a combined foundation garment for women's wear adapted to be worn beneath a gown having a low décolletage at the back and consisting of a brassière comprising a pair of breast supports constituted by two substantially triangular pieces of material overlapping secured together in front so as to have a common base line for part of their length together with a pair of shoulder straps and a lower part fitting closely to the wearer's hips and having in wear its upper edge at the back located approximately on the natural waistline, back connecting means comprising straps attached to the outer extremities of the said breast supports and arranged substantially in a wide angled V for attachment to the upper edge of said lower part of the garment near the middle of the back thereof, front connecting means comprising short oblique straps attached to the outer ends of said common base line of the breast supports and to the upper edge of said lower part of the garment leaving the portions of the lower edges of said breast supports outwardly of said common base line free; said short oblique straps and the free portions of the upper edge of said lower part of the garment located laterally thereof being shaped and positioned substantially in continuation of the inner upper edges of the breast supports to serve in conjunction with said front and back connecting means for producing tensions along said inner upper edges of the breast supports.

7. In a combined foundation garment for women's wear adapted to be worn beneath a gown having a low décolletage at the back and consisting of a brassière comprising a pair of breast supports constituted by two substantially triangular pieces of material overlapping and secured to

gether in front so as to have a common base line for part of their length together with a pair of shoulder straps, and a lower part fitting closely to the wearer's hips and having in wear its upper edge at the back located approximately on the natural waistline, back connecting means comprising a loop attached to the upper edge of said lower part of the garment at the middle of the back and a strap attached to the outer extremities of the said breast supports and passing through said loop, said strap being arranged substantially in a wide angled V and having its free ends connected to the upper front ends of the breast supports in line with the respective crossed inner upper edges of the supports to take up tension therethrough from said common base line of the breast supports and the upper edge of said lower part of the garment, the portions of the lower edges of said breast supports outwardly of said common base line being free; the free portions of the upper edge of said lower part of the garment located laterally of the said front connecting means being shaped and positioned substantially in continuation of the inner upper edges of the breast supports to serve in conjunction with said front and back connecting means for producing tensions along said inner upper edges of the breast supports.
